DANIEL S. COLBY AND ROBERT SCORER, OF TROY, NEW YORK, ASSIGNEES
TO COX, CHURCH & CO., OF SAME PLACE.

Design No. 2,589, dated February 26, 1867.

DESIGN FOR THE PLATES OF A COOK'S STOVE.

The Schedule referred to in these Letters Patent and making part of the same.

TO ALL WHOM IT MAY CONCERN:

Be it known that we, DANIEL S. COLBY and ROBERT SCORER, of Troy, in the county of Rensselaer, and State of New York, have invented or produced a new and original Design for Cook-Stove Plates, of which the following is a full, clear, and exact description, reference being had to the annexed drawings and to letters of reference marked thereon, forming a part of this specification, in which—

Figure 1 is a view of the side or jamb-plate, with oven doors.

Figure 2 is a view of the front upper plate, with fire doors; and

Figure 3 is a view of under front plate, being all respectively of the same stove.

Our said design for cook-stove plates is composed as follows: A, fig. 1, is a side or jamb-plate, of the shape or form as shown in said figure; B is the oven main door, having upon its panel the ornament C; the border moulding *a* of said door being, in form and ornamental configuration, the same as shown in said fig. 1. D is the extension oven door, having upon its panel the ornament E, and having a border moulding *b*, of the same configuration as that of oven door B. F is the end fire door, having the ornament G upon its panel, and the same pattern of moulding *c*, bordering its top and sides, as the oven doors; its bottom part being bagged or swelled out in form, as shown in the drawing. H H, fig. 2, represents the front upper plate with its front fire doors. Upon the sunk panels, at each end of said plate, are placed respectively the ornaments I and I'. J is one of the fire doors, having the ornament K arranged upon its panel, and having the same pattern of border moulding, *d*, as the fire door F aforesaid; the other fire door J' being, in ornamental design and configuration, the same as door J, as shown in annexed drawing. L L, fig. 3, represents the under front plate, having the panel M bordered by the ornamental moulding *e*, the same as shown in said figure.

What we claim as our invention and production, and desire to secure by Letters Patent, is—

The ornamental configuration and design for the plates of a cooking stove, the same as herein described, and shown in the annexed drawing.

DANL. S. COLBY,
ROBERT SCORER.
